METHOD OF TREATING HYDROCARBON DISTILLATES

Virden W. Wilson, Buffalo, N. Y., assignor to Buffalo Electro-Chemical Company, Inc., Buffalo, N. Y.

No Drawing. Application February 1, 1937,
Serial No. 123,481

10 Claims. (Cl. 196—29)

This invention relates to the treatment of hydrocarbon distillates and more particularly to a mode of procedure whereby sour distillates are sweetened.

5 A hydrocarbon distillate obtained by the distillation from petroleum is "sour" when upon treatment with an alkaline solution containing dissolved lead oxide, as, for instance, lead oxide dissolved in caustic soda, and elementary sulfur, a discoloration is produced at the interface of the gasoline and the aqueous solution. This test is generally designated as the "doctor" test; the alkaline solution containing lead oxide, the "doctor" solution. A positive doctor test indicates that the distillates contain sulfur compounds, wherein the group —SH is combined with an organic radical R or hydrogen.

20 As substantially all hydrocarbon distillates are sold according to rigid specification requiring that they be sweet, i. e., show a negative doctor test, therefore, all distillates containing —SH must be treated in some fashion to eliminate this group.

25 Heretofore, the method generally employed for sweetening sour distillates comprised reacting the undesirable sulfur compounds of the type containing the SH group with a reagent obtained by dissolving lead oxide in caustic alkali, sodium plumbite and thereafter adding elementary sulfur. By this procedure RSH compounds are changed to innocuous di-sulfides remaining in the distillate, or are removed from the distillate. In general, this sweetening procedure may be illustrated by the following chemical equation

35 It is generally recognized that the plumbite or doctor procedure is effective for sweetening gasoline or other sour distillates but suffers the disadvantage that the procedure is expensive and secondly, that it is necessary to add elementary sulfur in exact predetermined amounts in accordance with Equation 2 to prevent the addition of excess free sulfur which would produce a corrosive gasoline.

40 An object of the present invention, therefore, is the provision of a mode for sweetening sour petroleum distillates without the necessity of using sulfur with the production of a distillate showing a negative doctor test. Another object of the invention is to provide a method for sweetening sour distillates that is relatively more economical than the procedures heretofore used.

45 In accordance with the present invention, relatively water-free solutions of caustic alkali are added to the distillate to be sweetened in such fashion as to obtain intimate contact therewith, the mixture being treated with an oxidizing agent capable of changing the mercaptides to disulfides,

5 but not so vigorous as to attack unsaturated compounds present in the distillate. Thus, an alcoholic caustic solution substantially free of water is preferably employed in the procedure of the present invention, the alkali being either caustic soda or caustic potash, dissolved in substantially anhydrous alcohol, as, for instance, methyl alcohol, ethyl alcohol, propyl alcohol, or other water soluble alcohol. The concentration of caustic hydroxide dissolved in the alcohol may be any quantity consistent with the solubility of the caustic therein, although, in general, solutions of from about one-half normal to about two normal will be found to be practical for the procedure. The alcoholic caustic and the oxidizing agent may be added to the distillate concurrently or consecutively.

10 It is believed that upon the addition of the alcoholic caustic solution to the gasoline, any mercaptans contained in the gasoline are changed by the caustic alkali to mercaptides, the mercaptides being changed to disulfides upon reaction with the oxidizing agent.

15 In the practical operation of the procedure it has been found preferable to use an amount of alcoholic caustic substantially in excess of that theoretically required for the content of mercaptans in the distillate to be sweetened, since the time of contact required to obtain complete conversion of the mercaptan is considerably reduced and is brought within practical operating limits. In general, two and a half to five fold excess of alcoholic caustic above that required by the mercaptan present in the gasoline has been found satisfactory. Representative results are outlined in Table I below where 100 cc.'s of a crude gasoline containing 0.078% sulfur as mercaptan was agitated during a given time period of 10 minutes with the indicated normal caustic soda dissolved in substantially absolute methyl alcohol and the theoretical quantity of 100 volume hydrogen peroxide to oxidize the mercaptan sulfur.

Table I

cc.'s of normal alcoholic caustic	Percent of mercaptan sulfur converted
2	92
5	99.7
6	100

45 It will be noted that 2 cc.'s of normal caustic soda represent approximately the theoretical quantity of caustic alkali required to exactly react with the amount of mercaptan present in the sample of gasoline and that within the given time limit a two and one-half fold excess of caustic alkali permits a substantially complete removal of the mercaptan sulfur.

55

60

In general, the alcohol used in making the alcoholic caustic should be substantially anhydrous and contain less than about 5% of water.

- As is well known, the more acidic mercaptans, as, for instance, methyl and ethyl mercaptan and also hydrogen sulfide are readily removed by caustic wash and so are not troublesome in practice. In Table II is set forth the results of an investigation upon sweetening of a hydrocarbon distillate made sour by the addition thereto of specified mercaptans such as propyl, butyl, amyl and heptyl mercaptans. The sour distillate was treated with specified alcoholic alkali hydroxide solutions normal in strength and agitated 10 minutes and 30 minutes in the presence of a slight excess of hydrogen peroxide over that required for the conversion of disulfide.
- The mode of treatment on the experimental work was as follows: 100 cc. of the gasoline under test were pipetted into a clean glass bottle and 10 cc. of the caustic treating reagent were added. Immediately thereafter 0.2 cc. of 100 volume hydrogen peroxide was added. The bottle was stoppered with a clean new cork stopper and was shaken for the appropriate length of time. In the conclusion of this period of agitation the bottle was removed and an amount of distilled water equivalent to the amount of alcohol originally added was pipetted into the bottle. The water was shaken for a moment or two with the gasoline and the entire mixture allowed to settle into two layers, the upper of which was decanted, filtered to remove small amounts of still suspended alcohol and water and was then analyzed for mercaptan content, total sulfur, change in specific gravity and other items of interest. In the table methyl and ethyl alcohols are abbreviated in the usual way as MeOH and EtOH respectively.

Table II

Treating solution	Percent of sulfur as mercaptan left in solution	Percent of mercaptan sulfur converted in 10 min. contact	Percent of sulfur as mercaptan left in solution	Percent of mercaptan sulfur converted in 30 min. contact
PROPYL MERCAPTAN				
Original distillate	0.1067	100	0.1067	100
MeOH-NaOH	0.000	100	0.000	100
95% EtOH-NaOH	0.0109	88.5	0.0002	91.3
95% EtOH-KOH	0.000	100	0.000	100
Abs EtOH-KOH	0.000	100	0.000	100
BUTYL MERCAPTAN				
Original	0.1114	100	0.1114	100
MeOH-NaOH	0.000	100	0.000	100
95% EtOH-NaOH	0.0212	81.1	0.0156	86.1
Abs EtOH-KOH	0.000	100	0.000	100
AMYL MERCAPTAN				
Original	0.1029	100	0.1029	100
MeOH-NaOH	0.000	100	0.000	100
95% EtOH-NaOH	0.0291	72.2	0.0214	79.5
Abs EtOH-KOH	0.000	100	0.000	100
HEPTYL MERCAPTAN				
Original	0.1005	100	0.1005	100
MeOH-NaOH	0.000	100	0.000	100
95% EtOH-KOH	0.000	100	0.000	100
Abs EtOH-NaOH	0.0201	78.1	0.0068	92.6
Abs EtOH-KOH	0.000	100	0.000	100

In Table III is set forth the results of an investigation of the effect of aqueous caustic soda upon various higher mercaptans dissolved in gasoline, 100 cc.'s of the artificially soured gasoline being agitated with 10 cc.'s of normal caustic for the time indicated and the residual sulfur determined. The percent sulfur as mercaptan in the original samples was approximately 0.1%.

Table III

Treating solution	Mercaptan	Time of contact, minutes	Percent removal	10
Aq NaOH	Propyl	10	55.4	15
Do	Butyl	30	53.0	20.5
Do	Amyl	10	26.7	10.0
Do	Heptyl	30	13.4	1.5
		10	5.1	20
		30		

The mode of treatment contemplated in a plant process based on this experimental evidence would be as follows: Sour cracked gasoline which had been stabilized for the removal of most of the butane and all of the hydrogen sulfide is first contacted with a 15-25° Bé. solution of caustic soda. This may be obtained in part at least from the recovery still for methanol to be mentioned subsequently. The aqueous caustic treatment will remove the more acidic mercaptans and succeed in lowering the sulfur content of the gasoline by the amount of low molecular weight mercaptan removed. The caustic washed gasoline is then pumped through a mixing pump into a pipe coil. At the mixing pump a predetermined amount of alcoholic caustic containing sufficient potassium or sodium hydroxide to react with all the mercaptans present in the gasoline is added and an amount of concentrated hydrogen peroxide sufficient to insure sweetening is added at the same time. It has been found that better results can be obtained by such concurrent treatment with alcoholic alkali and peroxide rather than by mixing these constituents before adding them to the gasoline or first contacting with alcoholic alkali and then with hydrogen peroxide.

The product discharged from the pipe coil consists then of a dispersion of alcoholic caustic in gasoline. This will then be discharged into a settling tank whereupon at least half or more of the alcoholic caustic settles to the bottom and may be withdrawn in this concentrated condition for recirculation through the process. The gasoline is then passed into a washer where it is contacted with a vigorous scrubbing spray of water, the volume of water being kept as low as possible, yet sufficient employed to insure complete removal and separation of the aqueous alcoholic layer from the gasoline. The concentration of the alcohol in this layer will be 30-50%. Such treatment should leave less than one-half of 1% of the alcohol employed in the gasoline. This amount of loss will not appreciably affect treating costs since the volume of alcohol employed will be in the neighborhood of 5-7% of the volume of the gasoline treated. The sweetened water-washed gasoline can then be passed directly to storage while the alcohol extracted by the final water wash would be returned to a fractionating column, the heat from which could be supplied by exchangers in connection with the cracking still column condenser. The overhead from the alcohol fractionating column would be

condensed in the second set of heat exchangers to effect maximum heat recovery and the recovered methanol run to storage, thence to mixing tanks where fresh alcoholic caustic would be 5 added in quantities sufficient to insure adequate caustic present in the gasoline at all times. The process of treating and alcohol recovery can thereby be made cyclic and the amount of alcohol required for continuous operation will re- 10 main substantially constant and need be replaced only for slight losses due to carry-over in the gasoline or to such losses as may occur in fractionation.

From the foregoing it will be seen that the 15 present invention provides a method for sweetening sour hydrocarbon distillate by the use of a substantially water free solution of caustic alkali in conjunction with an oxidizing agent capable of changing mercaptides to disulfides, but 20 not attacking unsaturated compounds in the gasoline, that is to say, the percompounds, which are materials capable of generating hydrogen peroxide in solution.

What is claimed is:

- 25 1. The method of sweetening sour hydrocarbon liquid distillates which comprises treating the distillate with an alcoholic solution of caustic alkali and an oxidizing agent yielding hydrogen peroxide.
2. The method of sweetening sour hydrocarbon distillates which comprises treating the liquid distillate with substantially water free alcoholic caustic alkali and an oxidizing agent capable of yielding hydrogen peroxide.
3. The method of sweetening sour hydrocarbon distillates which comprises adding alcoholic caustic alkali to the liquid distillate and then treating the mixture with an oxidizing agent capable of yielding hydrogen peroxide.
4. The method of sweetening sour hydrocarbon distillates which comprises agitating the liquid distillate with alcoholic caustic alkali and an oxidizing agent capable of yielding hydrogen peroxide and capable of oxidizing mercaptides to disulphides.
- 45 5. The method of sweetening sour hydrocarbon distillates which comprises treating the liquid distillate with an amount of alcoholic caustic alkali having sufficient caustic content to change

the mercaptans in the sour distillate to mercaptides and treating the mixture with sufficient of an oxidizing agent yielding hydrogen peroxide to change the mercaptides to disulfides.

6. The method of sweetening sour hydrocarbon distillates which comprises treating the liquid distillate with alcoholic caustic alkali having a caustic content in excess of that required to change the mercaptans in the distillate to mercaptides and thereafter treating the mixture with sufficient hydrogen peroxide to render the distillate negative to the doctor test.

7. The method of sweetening sour hydrocarbon distillates which comprises treating the liquid distillate with an amount of alcoholic caustic alkali having sufficient caustic content to change the mercaptans in the sour distillate to mercaptides and treating the mixture with sufficient of an oxidizing agent capable of yielding hydrogen peroxide to change the mercaptans to disulfides and regenerate the alkali.

8. The method of sweetening sour hydrocarbon distillates which comprises treating the liquid distillate with 4-8% of an alcoholic caustic alkali, the alcohol being substantially anhydrous meth- 25 anol, having a caustic content in excess of the amount required to react with the mercaptans in the distillate and adding thereto at the same time sufficient hydrogen peroxide to render the distillate negative to the doctor test.

9. The method of sweetening sour hydrocarbon distillates which comprises treating the liquid distillate concurrently with 4-8% of a methanol solution of caustic alkali, having a caustic content sufficient to react with all the mercaptans 35 present in the distillate and a sufficient quantity of hydrogen peroxide to render the distillate negative to the doctor test with subsequent removal of the excess alcohol by water washing.

10. The method of sweetening sour hydrocarbon distillates which comprises adding to the 40 liquid distillate an alcoholic caustic alkali solution, the alcohol being chosen from the water soluble monohydric alcohols in substantial anhydrous condition, and concurrently treating the solution so obtained with an oxidizing agent capable of yielding hydrogen peroxide.
